Primary Examiner — Janice Hallmark(74) *Attorney, Agent, or Firm* — Barnes & Thornburg LLP(57) **CLAIM**

The ornamental design for an adhesive mounting base as shown and described.

DESCRIPTION

FIG. 1 is a perspective view of an adhesive mounting base in accordance with our new design;
 FIG. 2 is a front elevation view thereof;
 FIG. 3 is a rear elevation view thereof;
 FIG. 4 is a left-side elevation view thereof;
 FIG. 5 is a right-side elevation view thereof;
 FIG. 6 is a top plan view thereof; and,
 FIG. 7 is a bottom plan view thereof.
 Broken lines illustrate portions of the adhesive mounting base that form no part of the claimed design.
